TRUSS

Otha D. Arnsperger, Youngstown, Ohio

Application October 7, 1935, Serial No. 43,962

3 Claims. (Cl. 128—96)

This invention is a hernia support or truss and has as its object the provision of means for holding a hernia in its natural position without applying pressure over the internal or abdominal opening or ring, and which at the same time will serve to hold the internal and external inguinal or abdominal rings in their natural position.

As is well known by placing the pressure over the rings the nutriment is blocked thus retarding nature in bringing back tone to the rings and fascia. In accordance with the present invention however instead of placing the pressure over the rings pressure on both outer sides of the rings is applied forcing the rings into their natural position to the end that there will be no retardation of the nutriment and consequently nature will be assisted in restoring the necessary tone to the rings and fascia with the result of a cure except of course in very extraordinary cases of rupture or hernia.

The invention together with its objects and advantages will be best understood from a study of the following description taken in connection with the accompanying drawings wherein:

Figure 1 is a fragmentary elevational view of the truss embodying the features of the present invention.

Figure 2 is a plan view of the pad support, and said pad involving the features of the present invention.

Figure 3 is a detail view taken substantially on the line 3—3 of Figure 2.

Figure 4 is a plan view of a pad for treating double hernia.

Figure 5 is a plan view of a pad for treating a single hernia.

Figures 6, 7, 9 and 10 are detail views taken substantially on the lines 6—6, 7—7, 9—9 and 10—10 respectively of Figure 4.

Figure 8 is a detail sectional view taken substantially on the line 8—8 of Figure 5, and

Figure 11 is a perspective view of a ductile metal strap.

Referring to the drawings by reference numerals it will be seen that the hernia support or truss, in the preferred embodiment thereof, comprises, in accordance with the present invention a pad support consisting of a suitably shaped sheet 7 of leather or other suitable material to one face of which is stitched adjacent the marginal edges thereof as at 8 a covering 9 of any suitable soft material.

For use with the pad support there is provided, for treating a double hernia, a pad of the type

shown in Figure 4 and indicated generally by the reference numeral 10, while for treating a single hernia there is provided a pad of the type best shown in Figure 5 as indicated by the reference numeral 10a.

Referring more particularly to the pad 10 it will be noted that the same is formed entirely of sponge rubber, although of course any other suitable resilient material may be used. Further the pad 10 comprises two identically shaped bodies 11. Since the bodies 11 are identical in construction a detailed description of one will suffice. Thus it will be seen that each body 11 is formed as before intimated, sponge rubber or other resilient material and is substantially wedge-shaped in longitudinal section as will be clear from a consideration of Figure 7, presenting on one side a flat surface 12, and on a relatively opposite side an inclined surface 13. In plan the body 11 is somewhat oval shaped and has an opening 14 extending inwardly to about its transverse center from the thinnest end edge of the body. Due to the shape illustrated and described opposed side portions and the end portion of the pad will bear against opposed side and end portions of the abdominal ring and consequently pressure will be exerted against the ring and not over the openings of the abdominal ring to the end that the ring will be forced into its natural position, obviating any retardation of the nutriment and thus allowing nature to restore the necessary tone to the rings and fascia as hereinbefore alluded to. Further, on the face 13 which is presented toward the body the pad is dished out as at 15 to better accommodate itself to the contour of the abdomen and consequently insure use of the entire pad in exerting the desired pressure on the abdominal ring which is each affected.

The bodies 11 are formed integral with the respective opposite ends of a connecting bar or body 16 also of sponge rubber or similar resilient material, it being understood that the heads 11 and member 16 are molded together and in a single operation.

The pad 10 or 10a, as the case may be is confined on the holder between the body 7 of the holder and the cover sheet 9 thereof as clearly shown in the drawings, and to secure the pad in position the body sheet 7 and cover sheet 9 of the holder are stitched together as at 17 along all the continuous marginal edges of the members 11 and 16 as clearly suggested in Figure 2.

To aid in supplying the necessary pressure in the closing of the abdominal ring there is molded in the pad, 10 or 10a as the case may be a strap

18 of ductile metal. The strap 18 extends longitudinally through the connecting parts 16 of the pad to terminate within the bodies 11.

Also molded in the body portion 11 of the pad 5 are nuts 19 which receive screws 20 provided for pivotally connecting to the outer face of the pad pairs of plates, each pair of plates consisting of a plate 21, and a plate 22.

Each of the plates 21, 22 has an edge portion 10 folded over itself to provide a spring lip 23 for the reception of the frame part of a buckle 24 in a manner to detachably connect the buckle with a plate.

A body encircling belt 25 has its ends trained 15 through diagonally disposed guide strips 26 on the outer side of the pad support as clearly shown in Figure 1. Said ends of the belt 25 are crossed as also shown in Figure 1 and engage with the buckles 24 in a manner clearly shown. 20 By crossing the ends of the belt 25 where said ends connect in the manner just described with the pad holder a pull is exerted on the pad holder in a reverse direction and in directions most efficient for insuring the proper exertion of 25 pressure of the device against the abdominal ring.

When desired leg straps 27 may be used in a well known manner and are connected at one end of course with the belt 25 and at their other 30 ends said straps are engaged with the buckles 24 carried by the plates 22.

As before mentioned the pad 10 shown in Figure 4 is to be used in the treatment of a double hernia while the pad shown in Figure 5 is to be used for treating a single hernia. A pad such as shown in Figure 5 is of course suitable for treating the hernia of the left side but of course pads similar to those shown in Figure 5 and indicated by the reference numeral 10a may be 40 provided for treating hernia on the right side.

The pad 10a differs from the pad 10 only in that instead of having two identical body members 11, only one of said members is provided while the other member 11a at the end of the 45 member 16 opposite to the member 11 differs from the member 11 only in the absence of the opening 14, no such opening being required, since the pad 11a is not used in the healing of the hernia, but is desirable from the standpoint 50 that it renders more comfortable the wearing of the truss or support.

While it is believed that a clear understanding of the invention can be had by those skilled in the art, from the above detailed description, the 55 advantages and utility of the invention may be briefly set forth as follows:

The hernia support or truss is of course held in place on the body by the waist encircling belt 25. When properly positioned the finger portion 28 formed by the opening 14 in the body member 11 and which finger portions at their upper surfaces convex as indicated at 29 as best shown in Figure 10 will exert an inward squeeze or pressure on the abdominal ring at diametrical- 60 ly opposite sides of the ring in a manner to tend to force the ring into its natural position with the heel portion 30 of the body pad 11 fitting into the public notch just above the poupart's ligaments in a manner tending to hold the fingers 65 28 of the pad body 11 in position. Also when properly applied the abdominal ring will fit into the recess part 15 of the pad 11 in such a manner as to insure proper contact of all parts of the pad with the affected abdominal ring. In addition, 70 75 the ductile metallic strap 18 will readily bend

to adjust itself to the contour of the abdomen in such a manner as to aid greatly in supplying the necessary pressure from closing the abdominal ring.

When, as before stated but a single hernia 5 is being treated pad 10a will be used. When so used the body member 11a of the pad which also differs from the body 11 in that the side of the pad 11a presented toward the body is also slightly convexed as at 31 and as clearly shown in 10 Figure 8, will serve to prevent additional hernia or to protect the opposite side of the hernia.

In addition to the above features it will be apparent that the specific manner of fastening the ends of the belt 25 to the pad support will render it easy for the wearer to engage or release the ends of the belt in putting on or removing the support. Also in actual practice a non-elastic belt 25 will be found preferable, and by having said ends of the belt trained through 15 guide strips 27 the belt will not be likely to be continuously sliding up and down on the body 20 of the wearer.

Having thus described the invention, what is 25 claimed as new is:

1. A truss including a hernia support consisting of a sheet of flexible material, pad bodies disposed against the side of said sheet, a cover sheet for said pad bodies and the first named sheet secured to the first named sheet, and at least 30 one of said pad bodies consisting of a heel portion and integral spaced parallel finger portions, said pad body tapering from the heel to the free end of said fingers, and said fingers having convexed edges and said heel at the inner 35 ends of the fingers having a recess, said heel being adapted to fit into the public notch with said fingers bearing against opposite sides of the abdominal ring accommodated between said fingers and in said recess in a manner to receive 40 pressure from the fingers tending to force the fascia and ring together and into natural position for treating hernia.

2. A truss including a hernia support consisting of a sheet of flexible material, pad bodies 45 disposed against the side of said sheet, a cover sheet for said pad bodies and the first named sheet secured to the first named sheet, and at least one of said pad bodies consisting of a heel portion and integral spaced parallel finger portions, said pad body tapering from the heel to the free end of said fingers, and said fingers having convexed edges and said heel at the inner 50 ends of the fingers having a recess, said heel being adapted to fit into the public notch with said fingers bearing against opposite sides of the abdominal ring accommodated between said fingers and in said recess in a manner to receive 55 pressure from the fingers tending to force the fascia and ring together and into natural position for treating hernia, and the other of said pad bodies presenting a slightly convex surface at the side thereof adapted to bear against the body of the wearer.

3. A truss including a hernia support 60 consisting of a sheet of flexible material, pad bodies disposed against the side of said sheet, a cover sheet for said pad bodies and the first named sheet secured to the first named sheet, and at least one of said pad bodies consisting of a heel 65 portion and integral spaced parallel finger portions, said pad body tapering from the heel to the free end of said fingers, and said fingers having convexed edges and said heel at the inner 70 ends of the fingers having a recess, said heel 75

being adapted to fit into the public notch with said fingers bearing against opposite sides of the abdominal ring accommodated between said fingers and in said recess in a manner to receive pressure from the fingers tending to force the fascia and ring together and into natural position for treating hernia, and the other of said

pad bodies presenting a slightly convex surface at the side thereof adapted to bear against the body of the wearer, and a narrow solid piece connecting said pad bodies and extending between the inner edges of said bodies. 5

OTHA D. ARNSPARGER.
